SHAKER PACKAGE

Roderick W. Hoag, Melrose, Mass.

Application January 28, 1948, Serial No. 144,110

Term of patent 14 years

(Cl. D58—2)

To all whom it may concern:

Be it known that I, Roderick Wm. Hoag, a citizen of the United States, residing at Melrose, in the county of Middlesex and Commonwealth of Massachusetts, have invented a new, original, and ornamental Design for Shaker Package, of which the following is a specification, reference being had to the accompanying drawing, forming part hereof.

In the drawing:

Fig. 1 is a front elevational view of a shaker package showing my new design;

Fig. 2 is a side elevational view thereof; and

Fig. 3 is a cross sectional view taken on the line 3—3 of Fig. 1.

I claim:

The ornamental design for a shaker package, as shown.

RODERICK WM. HOAG.
